John Matthews Jr. of New York, N.Y. DES. 2440
Letter Patent No. 2440. Dated Sept. 25, 1866
Design for a Drinking Tumbler.

The Schedule referred to in these Letters Patent and making part of this design.

Will whom it may concern:

Be it known that I, John Matthews, Jr. of the City of New York, and State of New York, have originated a new Design for Drinking tumblers, of which the following is a full, clear and exact description, reference being had to the accompanying drawings forming part of this specification and in which, -

Figure 1 represents a side view of a drinking glass or tumbler made according to my Design, and

Figure 2, a vertical or longitudinal section thereof.

Like letters indicate like parts in both Figures.

A tumbler or drinking cup constructed according to my Design may be made of any suitable material. It differs from such vessels in ordinary use, however, in the form of its profile, and may be described as consisting for about two thirds from its base, of a shape resembling the inverted portion of a cone, while the remaining upper one third, or the mouth, is of a form that may be described as the frustum of a spheroid.

In the accompanying drawing A, represents the bottom or base of a tumbler, the lower portion B, of the body of which, for about two thirds from the base, corresponds in shape to an inverted frustum of a cone, or figure closely resembling the same, while the configuration of the remaining upper portion C is of a globular character, somewhat like the frustum of a spheroid.

Drinking tumblers thus formed present a symmetrical appearance, first, of the body gradually tapering upward and outward from the lower edge of the base, and such conical portion terminating at its top free from all abruptness by its gliding into junction with a curvilinear swell that tapers, or inclines inward at its upper end and gives an easy termination to the tumbler at its top.

DES. 2440

2 What I claim as my invention and desire to secure by Letters Patent is,
The Design for drinking tumblers herein set forth and as represented in the accom-
panying drawings.-

Witness,

J. W. Combs,

G. W. Reed,

John Matthews Jr.
